UNITED STATES PATENT OFFICE.

ALBERT J. COLE, OF MINNEAPOLIS, MINNESOTA.

EXPLOSIVE-ENGINE.

939,669.

Specification of Letters Patent. Patented Nov. 9, 1909.

Application filed March 5, 1909. Serial No. 481,301.

To all whom it may concern:

Be it known that I, ALBERT J. COLE, of Minneapolis, Hennepin county, Minnesota, have invented certain new and useful Improvements in Explosive-Engines, of which the following is a specification.

The object of my invention is to provide means in connection with a gas engine, whereby the piston will have a more rapid movement on the working stroke thereby utilizing the force of the explosion to the greatest advantage and at the same time having a leverage on the crank to the end that considerable power will be gained, and on the compression stroke an economy in power is effected by providing a leverage on the piston in compressing the charge.

A further object is to provide a connecting means between the crank shaft and the piston rod, which will eliminate side thrust in the cylinder.

A further object is to provide for a more rapid suction stroke, thus hastening the taking in of the charge and aiding the work of the carburetor on a four-cycle engine at slow speed.

A still further object is to provide for more time on the compression stroke to facilitate the discharge of burned gases and the taking in of a new charge between the working strokes on a two-cycle engine.

The invention consists generally in interposing a lever between the crank shaft and the connecting rod of an explosive engine, whereby there will be a gain in speed of the piston and a leverage on the crank during the working stroke, and a leverage on the piston during the compression stroke.

Figure 1 is a view partially in section, illustrating the position of the parts at a point about half way of the compression stroke of the engine. Fig. 2 is a similar view, illustrating the same parts at about the first quarter of the working stroke of the engine. Fig. 3 is a detail view, showing the connecting rod in section for very high speed four-cycle engines and illustrating the form of the lever and the manner of mounting the same. Fig. 4 is a detail, sectional view, illustrating the manner of mounting the sliding block of the crank shaft on the lever. Fig. 5 is a view similar to Fig. 1, illustrating a modified construction, Fig. 6

is a similar view, illustrating still another construction, Fig. 7 is a sectional view on the line X—X of Fig. 5, Fig. 8 is a perspective view of the crank shaft roller, Fig. 9 is a view similar to Fig. 5, illustrating means for adjusting a yoke, suspended on the lever, and on which yoke two of the crank rollers operate. Fig. 10 illustrates still another construction and form of adjustment, Fig. 11 is a sectional view on the line Y—Y of Fig. 10. Fig. 12 is a sectional view, showing the construction illustrated in Fig. 9.

In the drawing, 2 represents the cylinder of an explosion engine having a piston 3 and a connecting rod 4.

5 represents a bracket mounted on the cylinder, but any other suitable support may be provided.

6 is a crank shaft and 7 is a lever fulcrumed on the working side of the crank, as at 8 on the bracket 5, and having a pivotal connection at 9 with the connecting rod 4. This lever is preferably T-shaped in cross section, as shown in Fig. 4, but any other form may be used, if preferred.

10 is a box journaled at 11 on the crank shaft and arranged to slide back and forth on the lever 7 to accommodate itself to the different positions of the crank shaft and connecting rod. Suitable bearings are provided in the box to contact with the lever 7 and slide freely back and forth thereon. The lever 7, as arranged, may be termed one of the second class, as during the compression stroke, the power, viz., the momentum of the moving parts, is at one end, the fulcrum at the opposite end of the lever and the load, viz., the connecting rod, between. During the working stroke or after the explosion has taken place, the fulcrum of the lever will remain the same, the power will be transmitted through the connecting rod and the crank will be the load, the device remaining still a lever of the second class, as indicated in Fig. 2. The connection is made so that there will be a loss of time and gain of power on the compression stroke, while on the working stroke or after the explosion, there will be a more rapid movement of the connecting rod and piston, with an increased leverage of the piston on the crank, thus increasing the effective power

of the explosion. The loss of time upon the compression stroke renders this mechanism particularly applicable to a two-cycle engine, where it is of great importance to clear 5 the cylinder of the burned gases as rapidly and completely as possible before the admission of the fresh charge. By providing for a slower movement of the piston at this point, I am able to provide more time for the elimination of the burned gases and reception of 10 the new charge. I have also found that in a four-cycle engine my invention causes a more rapid suction stroke, thus drawing in the charge in less time and inducing a 15 stronger current of air thereby aiding the work of the carbureter.

Various ways may be devised for mounting the sliding box on the lever. In Fig. 4 I have shown anti-friction rollers 12 between 20 the box and the lever and adjustable plates 13 above the lever and between the top of the box 14 and anti-friction rollers 15, which are adapted to travel on the upper surface of the lever. Adjusting screws 16 permit 25 the adjustment of the plates 13, for the purpose of taking up the wear and preventing lost motion in the bearings of the anti-friction rollers 15. In Fig. 5, a guide rail 17 is provided, connected with the lever 7 by 30 threaded ends 19 and lock nuts 20 and forming with the lower surface of the lever 7 a guide way 21, in which an anti-friction wheel 22, mounted on the crank shaft, is adapted to roll on the rail 17. Similar and 35 larger wheels 23 are also mounted on the crank shaft and roll on the under surface of the lever 7. The rolls or anti-friction wheels fitting within the guideway 21 carried by 40 the crank shaft, may be made in several sections, two or more, as indicated in Fig. 9, to allow them to be placed readily on the crank of the shaft.

In Fig. 6, another form of lever 28, is shown, having a longitudinal opening 29 therein, wherein a box 30, mounted on the crank shaft, is adapted to slide. This box 45 preferably consists of plates arranged on each side of the lever and contacting with the edges of the recesses 29, with anti-friction rollers between the plates to operate in the recesses and bear on the edges thereof. Between the lever 28 and the piston, I have shown in this case, a yielding connection, 50 consisting of a sleeve 31, having a threaded connection at one end with the lower section of the connecting rod, a spring 32 being coiled about said rod within said sleeve to resist longitudinal strain on the rod, and adapted for use on high-speed, four-cycle 55 engines to relieve the jerk of the piston on the suction stroke.

In Fig. 9 the yoke 33 is illustrated adjustable on the lever by means of set screws 34 and yieldingly held by means of springs 35. 60 This yoke has lower side rails connected by

cross bolts 36 and the crank shaft has anti-friction wheels 37 to contact with said side rails and an intermediate wheel 38 to bear on the under side of the lever.

In Fig. 10, a guideway 39 is shown in the 70 lever 40, having lower side rails 41 that are adjustable vertically by means of bolts 42 and bear on anti-friction wheels 44 on the crank shaft. A large central wheel, corresponding to the one shown in Fig. 13, bears 75 on the upper rail of the guideway or the under surface of the lever. By means of these plates 41, all lost motion and wear can be taken up and a smooth, uniform movement of the anti-friction roller on the 80 crank shaft obtained.

I claim as my invention:—

1. The combination, with an explosive engine cylinder, its piston, connecting rod and crank shaft, of a lever having a pivotal connection at a fixed point, and a fixed pivotal connection with said connecting rod, and a sliding connection with said crank shaft, whereby a rapid piston movement is obtained on the working stroke and an increase 90 in leverage on the crank, substantially as described.

2. The combination, with an explosive engine cylinder, its piston, connecting rod and crank shaft, of a lever fulcrumed on the 95 working side of the engine and having a fixed pivotal connection with said connecting rod, and means carried by said crank shaft having a sliding anti-friction bearing on said lever whereby a leverage on the piston 100 will be obtained during the compression stroke.

3. The combination, with an explosive engine cylinder, its piston, connecting rod and crank shaft, of a lever having a fixed pivotal 105 connection at one end and pivoted at a fixed point intermediate to its ends to said connecting rod, and means connecting said lever and crank shaft whereby a more rapid movement of the piston will be obtained on 110 the working stroke and an increase in leverage on the crank during that stroke and a leverage on the piston during the compression stroke.

4. The combination, with an explosive engine cylinder, its piston, connecting rod and crank shaft, of a lever fulcrumed on the working side of said engine and crank shaft and having a fixed pivotal connection with said connecting rod, and anti-friction wheels 120 carried by said crank shaft and having an anti-friction bearing on said lever, substantially as described.

5. The combination, with an explosive engine cylinder, its piston and connecting rod, 125 of a crank shaft, a lever having a fixed pivot at one end on the working side of said crank shaft, and a fixed pivotal connection intermediate to its ends with said piston rod, a box having anti-friction bearings on said 130

lever and adapted to slide freely thereon, said box being journaled on said crank shaft and whereby a more rapid movement of the piston will be obtained on the working 5 stroke and an increasing leverage on the crank during that stroke, and a leverage on the piston during the compression stroke.

In witness whereof, I have hereunto set my hand this 2d day of March 1909.

ALBERT J. COLE.
